UNITED STATES PATENT OFFICE

2,460,810

SELF-ALIGNING CONICAL ROLLER

Trevor O. Davidson, Milwaukee, Wis., assignor
to Bucyrus-Erie Company, South Milwaukee,
Wis., a corporation of Delaware

Application November 1, 1944, Serial No. 561,464

9 Claims. (Cl. 308—220)

1

My invention relates to new and useful self-aligning conical rollers for turn-tables, more especially the turn-tables of self-propelled power-shovels, cranes, dragline excavators, and the like.

In such machines, the lower works frequently carries two superimposed annular conical roller-paths. Between these two paths run a series of conical rollers, carried by and supporting the upper works. These rollers normally rest on the lower path, but are capable of resting against the upper path to resist tipping of the upper works.

Even a slight wear of one of these rollers, and/or of either path engaged by it, and/or slight deflection of the structure, results in concentrating the load toward one edge of the bearing surface of the roller, thus causing over-stress at that point, and (if there are roller-bearings) requiring one set to bear the entire load.

Accordingly it is the principal object of my present invention to render these rollers self-aligning, to the end that the results of wear and deflection may be offset and eliminated.

A further object of my invention is to devise a new, simple, and efficient way to assemble the conical-roller, the self-aligning bearings, and the axle of my device.

In addition to my principal objects, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Figure 1 is a plan view, partly in section of the upper and lower works of an excavator embodying my invention.

Figure 2 is an enlarged vertical section of one of my rollers and associated parts, taken along either of the lines 2—2 of Figure 1.

Figure 3 is a vertical section, perpendicular to that of Figure 2, taken along the line 3—3 of Figure 2.

Turning now to Figure 1, we see that 11 is the lower works of my excavator, supported by creeping traction units 12, and supporting a rack track casting, which comprises an upper track 13, a lower track 14, and an internal ring gear 15. 16 is the upper works. It carries the engine

2

(not shown) and the excavating instrumentalities (not shown) and is capable of swinging through 30° about the pintle 11, by rotating the pinion 18, which depends from the upper works and engages the rack 15. The drive and controls (not shown), for the creeping traction 12, pass downwardly through pintle 11.

The frame of the upper works carries at each of its front corners an axle 19, on which rocks an 10 equalizer 20, which in turn carries two axles 21, each of which carries a conical roller 22, designed to run between tracks 13 and 14.

Substantially diametrically across the upper works from each of axles 19, is an axle 21 (directly carried by the frame), which carries a 15 conical roller 22, designed to run between tracks 13 and 14.

Turning now to Figures 2 and 3, let us consider the details of one of rollers 22, and its mounting.

20 The axle 21 is rigidly secured to the main frame 16 or to the equalizer 20, as the case may be, in any convenient manner, as by bolts 23. Inner race 25 of a roller bearing assembly has a spherical outer surface, and a conical inner surface. On the tapered end 24 of axle 21 is forced 25 the inner surface of inner race 25. Cooperating surfaces other than conical could be employed on axle 21 and inner race 25. Even a cylindrical surface could be employed if the fit were close enough, but some sort of wedge interaction is to 30 be preferred.

On this race run rollers 26, held spaced from each other by cages 27, which are well-known in the art. These rollers in turn engage the outer race 28, the inner surface of which is concentric with the spherical surface of the other race. Any other type of bearing, capable of limited universal movement, could be used; but preferably some type of anti-friction bearing, which term I shall 35 use in my claims as generic to roller bearings, ball bearings, and the like.

The conical roller, the roller-bearing, and the axle are assembled in the following manner.

40 A cap 29 is secured to the small end of conical roller 22 by screw-bolts 30, but (except for considerations of manufacturing convenience) might just as well be built integral therewith. This cap 29 has a recess 31, into which there fits very loosely a nut 32. Pins 33 project lengthwise from the small end of axle 21, and engage slots 34 in nut 32. This engagement serves to 45 prevent the nut from turning relative to the axle; and the use of slots, rather than, holes, serves to facilitate engagement without requiring too 50 much precision.

A combined guide and oil-seal 35 is secured to the large face of conical roller 22 by screw-bolts 36, and serves to hold the outer race 28 in place.

When conical roller 22, cap 29, nut 32, the complete roller-bearing assembly, and combined guide and oil-seal 35, are all thus assembled, the roller is placed between the two roller-paths 13 and 14. Axle 21 is then inserted through appropriate holes 37 and 38 in upper works 16 or equalizer 20 as the case may be, and is secured to it by screw-bolts 23. A little juggling may be necessary to get pins 33 to engage slots 34.

Bolt 39 is then inserted lengthwise through hole 40 in axle 21, and is screwed tight, thus causing nut 32 to seat inner race 25 firmly on tapered end 24 of axle 21.

Lubricating oil can be forced into the interior of the assembly through oil-fitting 41, hole 42, and hole 40 (which is sufficiently larger than bolt 39 for this purpose).

The form of roller-bearing employed, enables conical roller 22 to oscillate to take-up wear, misalignment, and deflection, in a vertical direction. It also permits some realignment in a horizontal direction, too much being prevented by guide 35 bearing on axle 21.

It should be noted that there is a slight clearance between guide 35 and axle 21; also between guide 35 and frame 16 or 20. This permits limited realignment, but prevents excessive realignment. A flexible element 43 maintains the oil-seal effect of guide 35, even during relative movement of guide 35 and axle 21.

Having now described and illustrated one form of my invention, I wish it to be understood that my invention is not to be limited to the specific form or arrangement of parts herein described and shown.

I claim:

1. In a roller assembly for turn tables, the combination of: the roller proper, having a central cavity; a self-aligning anti-friction bearing within this cavity; an axle; means for securing the axle to the inner race of the bearing, said means comprising a central hole in the inner race, a cooperating tightly fitting external conformation on the axle, a nut to bear against the inner race to force it onto the axle, and a bolt passing through the axle and engaging the nut; and means for securing the outer race of the bearing to the roller proper.

2. A roller assembly according to claim 1, further characterized by the fact that the cooperating surfaces of inner race and axle have a wedging contact.

3. A roller assembly according to claim 1, further characterized by the fact that the cooperating surfaces of inner race and axle have a conical contract.

4. A roller assembly according to claim 1, further characterized by the fact that the axle and the nut have cooperating guide means to limit their relative rotation.

5. A roller assembly according to claim 1, further characterized by having means to limit lateral oscillation of the roller proper with respect to the axle.

6. A roller assembly according to claim 1, further characterized by having means to limit lateral oscillation of the roller proper with respect to the axle, such means comprising a guide, secured to the roller proper and bearing loosely upon the axle.

7. A roller assembly according to claim 1, further characterized by having means to limit lateral oscillation of the roller proper with respect to the axle, such means comprising a guide, secured to the roller proper and bearing loosely upon the axle, and being integral with the means for securing the outer race to the roller proper.

8. A roller assembly according to claim 1, further characterized by having means to limit lateral oscillation of the roller proper with respect to the axle, such means comprising a combined guide and oil seal, secured to the roller proper and bearing loosely upon the axle; and by having means for admitting oil into the interior of the assembly through the axle.

9. A roller assembly according to claim 1, further characterized by the fact that the central cavity has such conformation at its inner end as to hold the nut aligned for insertion of the bolt.

TREVOR O. DAVIDSON.
